UNITED STATES PATENT OFFICE.

WILLIAM P. PITTS, OF INDEPENDENCE, MISSOURI, ASSIGNOR TO IRVING-PITT MANUFACTURING COMPANY, OF KANSAS CITY, MISSOURI, A CORPORATION OF MISSOURI.

LOOSE-LEAF HOLDER.

1,284,764.

Specification of Letters Patent. Patented Nov. 12, 1918.

Application filed July 15, 1914. Serial No. 851,079.

To all whom it may concern:

Be it known that I, WILLIAM P. PITTS, a citizen of the United States, residing at Independence, in the county of Jackson and State of Missouri, have invented a certain new and useful Improvement in Loose-Leaf Holders, of which the following is a specification.

My invention relates to improvements in loose leaf holders.

It relates particularly to loose leaf books having coöperating segmental leaf engaging hooks. With structures of this type, if the hooks are fairly well filled with loose leaves, it is sometimes difficult and inconvenient to swing them to the open position.

One of the objects of my invention is to provide a simple and efficient mechanism for swinging the hook carrying members to the open position.

A further object of my invention is to provide a housing for the hook carrying members having end caps which, when forced toward each other will effect an opening of the hook carrying members.

Other novel features of my invention are hereinafter fully described and claimed.

In the accompanying drawings which illustrate my invention as applied to loose leaf books,

Figure 1 is a top view of one form of my invention, showing the hooks in the closed position, the metal parts being shown secured to the back of a book, portions of the covers thereof being broken away, and a portion of the cover plate being broken away.

Fig. 2 is a plan view of the metal parts shown in Fig. 1, the cover plate being removed.

Fig. 3 is a plan view showing the hook carrying members in the open position and partly broken away, the cover plate being removed.

Fig. 4 is a bottom view of what is shown in Fig. 2.

Fig. 5 is a longitudinal section on the plane of the line 6—6 of Fig. 1 with the metal parts detached from the back of the book, the cover plate being removed and the hooks shown in the open position.

Fig. 6 is a sectional view on the line 6—6 of Fig. 1 with the hooks shown in the closed position.

Fig. 7 is a cross section on the line 7—7 of Fig. 6.

Fig. 8 is an enlarged cross section on the plane of the line 8—8 of Fig. 6, the cover plate being present.

Fig. 9 is a perspective view of one of the end caps.

Fig. 10 is an end elevation of one of the end caps.

Fig. 11 is an enlarged longitudinal sectional view similar to that shown in Fig. 6, one end only of the mechanism being shown. In this view, the metal parts are shown in the closed position.

Fig. 12 is a cross section on the line 12—12 of Fig. 11.

Fig. 13 is a view similar to Fig. 11, the movable parts being shown in the open position.

Fig. 14 is a cross section on the line 14—14 of Fig. 13.

Fig. 15 is a plan view of another form of my invention, the hooks being shown closed, and part of the cover plate being broken away.

Fig. 16 is an enlarged longitudinal central vertical sectional view of the device shown in Fig. 15, the cover plate being removed and other parts broken away.

Fig. 17 is a cross section on the line 17—17 of Fig. 16, the hooks being shown in the closed position.

Fig. 18 is a view similar to Fig. 16, the hooks being shown in the open position.

Fig. 19 is a cross section on the line 19—19 of Fig. 18.

Similar reference character designate similar parts in the different views.

Referring first to Figs. 1 to 14, 1 designates a spring plate, preferably arcuate and having inwardly turned longitudinal flanges 2 forming seats respectively for the outer edges of two operatively connected hook carrying members, preferably comprising horizontal plates 3, the inner edges of which are operatively connected by buttons 4, each having heads respectively above and below the plates 3.

The plates 3 are respectively provided with coöperating inwardly curved hooks 5 and 6 adapted to form rings for holding loose leaves in a manner well understood.

The spring plate 1 exerts a pressure

55

100

105

against the plates 3 tending to hold them in either the open or closed position. Said spring plate is adapted to be mounted on the inner side of the back 7 of a book having 5 the usual covers 8.

A cover plate 10 may be mounted on the top of the spring plate 1 as shown in Figs. 1 and 8.

Longitudinally slidable on the spring 10 plate 1 are two tubular end caps 9 which respectively embrace the respective ends of the spring plate 1 and cover plate 10.

Each cap 9 is provided with a longitudinal extension 11 longitudinally slidable in 15 and conformed to the spring plate 1. Each extension 11 has a longitudinal slot 12 through which extends an upwardly projecting tongue 13, two of which are provided in the spring plate 1 as shown in Figs. 5 20 and 6.

In the form of my invention shown in Figs. 1 to 14, the ends of each plate 3 are respectively provided with upwardly and outwardly inclined projections 14 adapted 25 to be operatively engaged by inclined cam faces 15, of wedges 16, formed by raising portions of the extensions 11 respectively adjacent to the outer ends of the slots 12.

The inclined surfaces 14 and 15 are preferably disposed at approximately an angle of 45 degrees from the horizontal.

When the caps 9 are forced inwardly toward each other by pressure applied to the outer ends thereof, the wedges 16 by engaging 35 the inclined projections 14 will force the hook plates 3 and the hooks 5 and 6 from the closed position shown in Figs. 11 and 12 to the open position shown in Figs. 13 and 14.

When the hooks 5 and 6 are forced to the 40 closed position, the downward swinging of the plates 3 will cause the projections 14 to impinge against the inclined surfaces 15 of the wedges 16, thereby forcing said wedges and the caps 9 to the outer position shown in 45 Figs. 6 and 11. The inclination of the surfaces 15 permits this to be easily effected.

As shown in Figs. 1 and 8, the caps 9 by 50 respectively embracing the ends of the cover plate 10, hide the end joints, thereby providing a construction which is ornamental as well as efficient.

The projections 13 on the spring plate 1 limit the outward movement of the caps 9. Said projections are formed by being 55 punched from the spring plate 1, thereby leaving openings 17, Fig. 4, through which a pointed instrument, not shown, may be inserted for the purpose of lifting the inner ends of the extensions 11, if it is desired to 60 bodily withdraw the caps 9 from the spring plate 1.

Each cap 9 is provided with downwardly and inwardly turned flanges 18 which embrace similar flanges 19 provided at the lon-

gitudinal edges of the cover plate 10, and 65 which embrace the flanges 2 of the spring plate 1. The caps 9 are thus guided and retained in their respective operative positions.

In the form of my invention shown in 70 Figs. 15 to 19, the parts are constructed in most respects similarly to corresponding parts in the form which I have just herein-before described.

In the form shown in Figs. 15 to 19, the 75 hook plates designated by 3' are pivotally mounted in a spring plate 1 in the same manner as described with reference to the other form of my invention, and have their inner edges operatively connected by double headed buttons 4', corresponding to the buttons 4, excepting that the lower heads of the buttons 4' are rounded or inclined and respectively engage the inclined surfaces 15 80 of the wedges 16 formed in the extensions 11 85 of the caps 9. In the plates 3', the projections 14 such as are provided in the plates 3 of the other form of my invention, are eliminated, their function of engaging with the wedges 16 being effected by the buttons 4'. 90

In the operation of the form of my invention shown in Figs. 15 to 19, when the caps 9 are forced inwardly, the inclined surfaces 15 of the wedges 16 will engage respectively the rounded lower heads of the buttons 4', thereby swinging the hook carrying members 3' and the hooks 5' and 6' carried thereby from the position shown in Figs. 16 and 17 to the open position shown in Figs. 18 and 19.

By forcing together the hooks 5' and 6', the plates 3' together with the buttons 4' will be forced downwardly, thereby forcing outwardly the caps 9 through the intermediacy of the wedges 16 and buttons 4'. 100

I do not limit my invention to the structures shown and described, as modifications, within the scope of the appended claims, may be made without departing from the spirit of my invention.

Having thus described my invention, what I claim and desire to secure by Letters Patent, is:—

1. A loose leaf holder comprising coöperating leaf engaging members, a spring plate pivotally holding said members, and an operating member slidable in one direction for rocking said members and retractable by said members.

2. A loose leaf holder comprising coöperating leaf engaging members, a spring plate pivotally holding said members, and means including a wedge movable in one direction for rocking said members, the wedge being retractable by said members.

3. A loose leaf holder comprising coöperating leaf engaging members, a spring plate pivotally holding said members, and

means including a sliding wedge movable in one direction for locking said members and retractable by said members.

4. A loose leaf holder comprising coöperating leaf engaging members, a spring plate pivotally holding said members, a member operatively connecting said members, and a sliding member adapted to engage said connecting member for rocking said leaf engaging members.

5. A loose leaf holder comprising coöperating leaf engaging members, a spring plate pivotally holding said members, a member operatively connecting said members, and a wedge adapted to engage said connecting member for rocking said members.

6. A loose leaf holder comprising coöperating leaf engaging members, a spring plate pivotally holding said members, a member operatively connecting said members and a slideable member adapted to engage said connecting member for rocking said leaf engaging members and retractable by said connecting member.

7. A loose leaf holder comprising coöperating leaf engaging members, a spring plate pivotally holding said members, a member operatively connecting said members, and a wedge adapted to engage said connecting member for rocking said leaf engaging members and retractable by said connecting member.

8. A loose leaf holder comprising coöperating leaf engaging members, a spring plate pivotally holding said members, a member operatively connecting said members, and a wedge adapted to slideably engage said connecting member for rocking the leaf engaging members and retractable by said connecting member.

9. A loose leaf holder comprising coöperating leaf engaging members, a spring plate pivotally holding said members, a connecting member engaging said members and having a cam surface, and an operating member adapted to engage said cam surface for rocking said leaf engaging members.

10. A loose leaf holder comprising coöperating leaf engaging members, a spring plate pivotally holding said members, a member operatively engaging said members and having a cam surface, and a wedge adapted to engage said cam surface for rocking said leaf engaging members.

11. A loose leaf holder comprising coöperating leaf engaging members, a spring plate pivotally supporting and adapted to hold said members open or closed, and means including a slideable wedge for rocking said members to the open position, the inclination of the wedge being such that the wedge will be retracted upon the closing movement of said members.

12. A loose leaf holder comprising coöperating leaf engaging members, a spring plate pivotally supporting and adapted to hold said members open or closed, and means including a wedge, having an inclination of substantially 45 degrees to the line of movement of said wedge, for rocking said members.

13. A loose leaf holder comprising coöperating leaf engaging members, a spring plate pivotally supporting and adapted to hold said members open or closed, and a sliding member engaging said connecting member for rocking said leaf engaging members.

14. A loose leaf holder comprising coöperating leaf engaging members, a spring plate pivotally supporting said members and adapted to hold them open or closed, a member operatively connecting said members, and a sliding wedge engaging said connecting member for rocking said leaf engaging members.

15. A loose leaf holder comprising coöperating leaf engaging members, a housing for said members including a longitudinally movable closure for one end thereof and a spring plate for holding said members open or closed, and means actuated by the closure for rocking said members.

16. A loose leaf holder comprising coöperating leaf engaging members, a housing therefor including a longitudinally movable closure for one end thereof provided with a wedge, and a spring plate for holding said members open or closed, and means actuated by said wedge for rocking said members.

17. A loose leaf holder comprising coöperating leaf engaging members, a housing therefor including a spring plate for holding said members open or closed, a cover plate, and a cap slideably covering one set of ends of said plates, and means actuated by said cap for rocking said members.

18. A loose leaf holder comprising coöperating leaf engaging members, a housing therefor including a spring plate for holding said members open or closed, a cover plate, and a slideable cap covering one set of ends of said plates and provided with a wedge, and means actuated by the wedge for rocking said members.

19. A loose leaf holder comprising coöperating leaf engaging members, a housing therefor including a spring plate for holding said members open or closed and a longitudinally movable closure for one end of the housing, and a member operatively connecting said members and adapted to coöperate with said closure for rocking said leaf engaging members.

20. A loose leaf holder comprising coöperating leaf engaging members, a housing therefor including a spring plate for hold-

ing said members open or closed, and a longitudinally movable closure for one end of said housing provided with a wedge, and a member operatively connecting said members and adapted to coöperate with said wedge for rocking said leaf engaging members.

21. A loose leaf holder comprising coöperating leaf engaging members, and two wedges adapted to be moved simultaneously in opposite directions for forcing said members to the open position.

22. A loose leaf holder comprising coöperating leaf engaging members, two wedges, and means by which, when said wedges are moved toward each other, said members will be rocked.

23. A loose leaf holder comprising coöperating leaf engaging members, two wedges, and means for rocking said members when said wedges are moved simultaneously in opposite directions, the wedges being retractable by said members on the closing movement thereof.

24. A loose leaf holder comprising coöperating leaf engaging members, a spring for holding said members open or closed, two longitudinally movable members, and means actuated by said members when moved in opposite directions for rocking said leaf engaging members.

25. A loose leaf holder comprising coöperating leaf engaging members, a spring for holding said members open or closed, two wedges, and means actuated by said wedges when moved in opposite directions for rocking said members.

26. A loose leaf holder comprising coöperating leaf engaging members, and means including two wedges for rocking said leaf engaging members when said wedges are moved toward each other, the arrangement being such that the wedges will be retracted in the opposite direction by the closing movement of said leaf engaging members.

27. A loose leaf holder comprising coöperating leaf engaging members, a spring for holding said members open or closed and pivotally supporting said members, two longitudinally movable members, and means actuated by the last named members, when moved in opposite directions, for rocking said leaf engaging members.

28. A loose leaf holder comprising coöperating leaf engaging members, a spring plate for holding said members open or closed and pivotally supporting said members, two wedges, and means actuated by said wedges when moved in opposite directions for rocking said members.

29. A loose leaf holder comprising coöperating leaf engaging members, a spring plate for holding said members open or closed and pivotally supporting said mem-

bers, two wedges, and means actuated by said wedges, when moved in opposite directions, for rocking said members, said means serving to retract said wedges, when the leaf engaging members are rocked to the closed position.

30. A loose leaf holder comprising coöperating leaf engaging members, a housing therefor including two longitudinally movable closures at the ends thereof respectively, and a spring plate for holding said members open or closed, and means actuated by said closures for rocking said members.

31. A loose leaf holder comprising coöperating leaf engaging members, a housing therefor including a spring plate for holding said members open or closed and two longitudinally movable closures respectively provided with wedges, and means actuated by said wedges for rocking said members.

32. A loose leaf holder comprising coöperating leaf engaging members, a housing therefor including a spring plate for holding said members open or closed, a cover plate on said spring plate, and two longitudinally movable closures at the ends respectively of said plates, and means actuated by said closures for rocking said leaf engaging members.

33. A loose leaf holder comprising coöperating leaf engaging members, a housing therefor including a spring plate for holding said members open or closed, a cover plate on said spring plate, and two longitudinally movable closures at the ends respectively of said plates provided respectively with wedges, and means actuated by said wedges for rocking said leaf engaging members.

34. A loose leaf holder comprising coöperating leaf engaging members, a housing therefor including a spring plate for holding said members open or closed, and two end members at the respective ends of said plate, a member operatively connecting said leaf engaging members, and means actuated by said end members for rocking said leaf engaging members when the end members are moved in opposite directions.

35. A loose leaf holder comprising coöperating leaf engaging members, a housing therefor including a spring plate for holding said members open or closed, and two end members at the respective ends of said plate and provided respectively with wedges, and members operatively connecting said leaf engaging members, and adapted to respectively engage said wedges for rocking said leaf engaging members.

36. A loose leaf holder comprising coöperating leaf engaging members, a member operatively connecting said two members

and having an inclined surface, and a slide-
able wedge adapted to engage said inclined
surface for rocking said members.

37. A loose leaf holder comprising co-
operating leaf engaging members, a double
headed button operatively connecting said
members, and a slideable wedge adapted to
engage one of said heads for rocking said
members.

10 38. A loose leaf holder comprising co-
operating leaf engaging members, a double
headed button operatively connecting said
members, one of the heads having an in-
clined surface, and a movable member for
15 engaging said surface for rocking said mem-
bers.

39. A loose leaf holder comprising co-
operating leaf engaging members, a double
headed button operatively connecting said
members, one of the heads having an in-
clined surface and the wedge adapted to en-
gage said surface for rocking said members.

20 40. A loose leaf holder comprising co-

operating leaf engaging members, a housing
therefor comprising a spring plate for hold-
ing said members open or closed, a cover
plate on said spring plate, and two slideable
tubular caps respectively embracing the ends
of said cover plate, and means actuated by
said caps for rocking said members. 25

41. A loose leaf holder comprising co-
operating leaf engaging members, a housing
comprising a spring plate for holding said
members open or closed, a cover plate on
said spring plate, and two slideable tubular 30
caps provided respectively with wedges and
embracing respectively the ends of said
cover plate, and means actuated by said
wedges for rocking said members.

In testimony whereof I have signed my 40
name to this specification in presence of two
subscribing witnesses.

WILLIAM P. PITTS.
